F. M. DORE

ROLLER SKATE

Filed Oct. 2, 1924

Inventor

Frank M. Dore,

By *Clarissa A. O'Brien*

Attorney

UNITED STATES PATENT OFFICE.

FRANK M. DORE, OF BUTTE, MONTANA.

ROLLER SKATE.

Application filed October 2, 1924. Serial No. 741,196.

This invention relates to improvements in roller skates and particularly to improvements in the construction of the truck and truck mountings, the construction of the forward and rear sections of the sole plate, and the means for permitting the adjustment thereof and to the clamping device, for securing the sole of the shoe to the skate.

An object of the invention resides in providing a special construction of the forward and rear sections of the sole plate, to permit the relative adjustment thereof, and a specially constructed locking means for securing said sections in adjusted relation having a reciprocated member mounted in the rear section provided with locking projections adapted to extend through registering openings in the front and rear sections of the sole plate, and to be retained normally in one position for holding said plates normally in adjusted relation.

The invention also includes other objects and improvements in the details of construction and arrangement of the parts, which are more particularly pointed out in the following description and in the claims directed to the preferred form of the invention, it being understood, however, that various changes in the details of construction and arrangement of these parts may be made, without departing from the spirit and scope of the invention as described and claimed.

In the drawing, forming a part of this application:

Figure 1 is a side elevation of a skate, constructed in accordance with this invention, one of the rear wheels being omitted and the axle therefor shown in section.

Figure 2 is a plan view of the skate shown in Figure 1.

Fig. 3 is a fragmentary bottom plan of the central portion of the skate showing the locking device.

Fig. 4 is an enlarged detail sectional view taken on the line 4—4 of Fig. 1, showing the locking device.

The toe plate of the skate comprises forward and rear sections 1 and 2 respectively, which are constructed and assembled for relative adjustment to change the size of the skates, while the rear section 2 is formed with the usual heel plate 3, to which is secured the strap sections 4, by which the heel portion of the skate may be secured to the shoe of the wearer.

To provide for said adjustable connection between the forward and rear sections 1 and 2 of the sole plate, the forward section 1 is provided with a rearwardly extending tongue 6, which is formed with a central longitudinal slot 7, adjacent to which and on the opposite sides thereof are a plurality of aligned openings 8, arranged in pairs to correspond with aligned pairs of openings 9, in the forwardly extending slotted tongue 60 10, carried by the rear section 2, which tongue is adapted to extend through the slot 11 in the front section 1, so that the nut 12 carried by the front section will slidably engage in the slot formed therein as indicated 65 at 13. A locking member illustrated particularly in Figures 1 and 7 comprises a plate member 14 from the central portion of which projects a stud 15, adapted to extend through the slots 7 and 13 of the front and 70 rear sections of the sole plate respectively, so that the same will be maintained in aligned relation at all times, and particularly during the adjustment thereof for changing the length of the sole plate to fit a different size of shoe. This plate member 14 carries a pair of depending pins 16, which are adapted to extend through the pairs of aligned openings 8 and 9 respectively, in the front and rear sections 1 and 2, so as 75 to lock said sections in a desired position of adjustment. An arm member 17 is mounted on the stud 15, and has eyes formed in the opposite ends thereof adapted to receive the ends of the pins 16, as clearly 80 shown in Figure 4.

The arm member 17 is carried by the upper end of the coil spring 18, the lower end of which is fitted against a nut 19, threaded on the lower end of the said pin 15, for normally maintaining said spring under tension and moving the plate 14 into engagement with the tongue 6 on the front section of the sole plate, so that the pins 16 will engage in the openings in the respective sections 85 100 when in alignment or registry, and hold said sections in fixed adjusted relation.

From the foregoing description, it should be readily appreciated that a simple, yet efficient construction has been provided for 105 constructing and mounting the front and rear sections of the sole plate for relative adjustment, while at the same time they are constantly maintained in proper aligned relation, in any position of adjustment, as 110

well as during the adjustment thereof, together with the provision of the locking means for holding them fixed in an adjusted relation, which is readily moved to an inoperative position to permit the adjustment of the plate sections, without removing any part thereof which is likely to become lost, and which will readily reengage in the aligned openings in the sections of the sole plate, for again permanently securing them in adjusted position.

What is claimed is:

1. A skate comprising a sole plate formed of forward and rear sections having interfitting overlapped portions adapted for relative sliding movement to adjust the size of said skate, a locking member having a shank slidably extending through said section and provided with depending pins each of said sections being formed with a plurality of openings arranged in predetermined relation therein adjacent the slot in said tongue and adapted to receive said pins, and resilient means connected with said shank for normally operating said locking member to project the pins through the openings in said

sections for locking the same in adjusted relation.

2. A skate comprising a sole plate having forward and rear sections, said forward section having a rearwardly extending tongue formed with a longitudinal slot, said rear section having a forwardly extending tongue slotted longitudinally, and each of said sections being formed with a plurality of openings arranged in predetermined relation therein adjacent the said slot in said tongue, a locking member including a plate having a depending shank slidably extending through the slotted portion of said tongue of each of said sections, said plate carrying depending pins adapted for engagement in the openings formed in said sections, and a spring having an abutment disposed toward said sole plates connected to said shank for normally operating the locking member and plate to position the depending pins in predetermined openings in each of said sole sections for retaining the same in adjusted positions.

In testimony whereof I affix my signature.

FRANK M. DORE.
